UNITED STATES PATENT OFFICE.

SIMON HAMBURGER, OF NEW YORK, N. Y., ASSIGNOR TO HAMBURGER & CO., OF NEW YORK, N. Y., A CORPORATION OF VIRGINIA.

MAGIC LANTERN.

SPECIFICATION forming part of Letters Patent No. 736,093, dated August 11, 1903.

Application filed February 11, 1903. Serial No. 142,946. (No model.)

To all whom it may concern:

Be it known that I, SIMON HAMBURGER, a citizen of the United States, residing in New York, borough of Manhattan, and State of New York, have invented certain new and useful Improvements in Magic Lanterns, of which the following is a specification.

In the magic lanterns which have been heretofore made the body of the lantern or dark room (camera obscura) has been made of sheet metal, which has the disadvantages that owing to the heat of the lamp or other source of light at the interior of the same it soils the fingers when in use and that the sheet metal, being a conductor of heat, becomes hot and consequently burns the fingers when passing the slides through between the body of the camera and the lens-tube.

The object of this invention is to so improve toy magic lanterns that the objections referred to are avoided and not only a cleaner magic lantern is obtained, but also one which presents a more ornamental appearance than the sheet-metal magic lanterns heretofore in use, and for this purpose the invention consists of a magic lantern the body of which is composed of a sheet-metal top and bottom, sheet-metal corner-pieces, vertical posts connecting the top and bottom, and side and end walls made of tiles or other panels, as will be fully described hereinafter, and finally pointed out in the claims.

In the accompanying drawings, Figure 1 represents a side elevation of my improved magic lantern; and Fig. 2 is a horizontal section on line 2 2, Fig. 1, drawn on a larger scale.

Similar letters of reference indicate corresponding parts.

Referring to the drawings, A represents the body of my improved magic lantern, the top and bottom as well as the corners of which are made of sheet metal in the usual manner. The bottom B is provided with ornamental feet b and openings o for permitting the ingress of air to the lamp or other source of light supported on a plate or disk p at the interior of the body A. The rear wall of the body is made of sheet metal and provided with a hinged door d for permitting the insertion or

removal of the lamp or other source of light 50 in the usual manner. The side walls and opposite end wall of the body are formed of panels C, which are made of clay tiles, enameled steel, or other vitreous material ornamented in any suitable manner on the outside, 55 so as to improve thereby the appearance of the magic lantern. The panels C are supported by the interior and exterior sheet-metal corners D' D. The interior corners D' are connected at the top by stays m and the 60 exterior corners D are held in position by the lower plate H, provided with upwardly-extending flanges h, and the upper plate L, provided with downwardly-extending flanges l. With the bottom plate H are connected rods 65 or upright posts E, screw-threaded at their upper ends and passing upwardly in and between the sheet-metal corners until they protrude beyond the upper plate L. The upright posts are provided with ball-shaped terminals 70 at their upper screw-threaded ends, and when these are screwed down they clamp the sheet-metal corners between the upper and lower plates. The magic lantern may be easily taken apart for cleaning or repairing or replacing 75 the panels should some be broken.

On the top of the body A is supported the chimney F, by which the products of combustion are conducted off. The lens-tube G is arranged in the front tile wall and is supported on the guide-frame G', through which the slides are passed in the usual well-known manner.

The use of tile panels for the side and end walls of the magic lantern not only improves 85 the ornamental appearance of the same, but prevents the heating of the body and the sweating of the same by the heat of the lamp, so that the magic lantern can be handled when in use and is much neater and cleaner than 90 the sheet-metal structures heretofore in use.

Having thus described my invention, I claim as new and desire to secure by Letters Patent—

1. In a magic lantern, the combination, of 95 a body having the sides and end walls of tiles, sheet-metal top and bottom, and sheet-metal corner-pieces, with means for clamping the

tiles and retaining corner-pieces between the top and bottom for holding the tiles in position, substantially as set forth.

2. In a magic lantern, the combination, with
5 a top and bottom of sheet metal, of tile panels
forming the side and end walls of the body of
the lantern, angular sheet-metal pieces at the
exterior corner of the tiles for retaining the
same in position, upright posts between the
ends of the tiles and angular corner-pieces
connecting the top and bottom, and means at

the upper ends of the posts for clamping the corner-pieces between the top and bottom for supporting the tiles, substantially as set forth.

In testimony that I claim the foregoing as 15
my invention I have signed my name in presence of two subscribing witnesses.

SIMON HAMBURGER.
